UNITED STATES PATENT OFFICE

CARL B. PARSONS, OF DETROIT, MICHIGAN

LOADING BLOCK

Application filed February 24, 1928. Serial No. 256,519.

My invention relates to an improved vehicle wheel chock adapted primarily for use as a loading block in the shipment of motor vehicles.

5 An object is to provide an improved vehicle wheel chock formed of sheet metal which is of a strong sturdy construction and is light in weight and inexpensive as to cost. If desired, it may be retained for reuse but a meritorious characteristic is that it is so cheap 10 in price that it may be thrown away after use.

An advantageous feature lies in the provision of a vehicle chock which is formed from a single sheet of light weight sheet metal 15 by a relatively simple stamping operation and yet which possesses sufficient strength to effectively serve its purpose in the use for which it is intended.

Other advantages and desirable features 20 of my invention will more fully appear from the following specification, appended claims and accompanying drawing, wherein,—

Fig. 1 is a rear elevation of a loading block embodying my invention.

25 Fig. 2 is a sectional view taken on the line 2—2 of Fig. 1.

Fig. 3 is a horizontal sectional view taken on line 3—3 of Fig. 2, and

30 Fig. 4 is an end view of a block of modified form.

My improved block is stamped out of a single piece of light weight sheet metal longitudinally corrugated as appears at 10 to lend strength and rigidity thereto. The metal sheet 25 is so formed as to provide an arcuate portion 12 shaped to embrace the periphery of the road wheel of the vehicle and each end is bent downwardly as at 14 forming supporting legs. The supporting legs are not only bent 30 downwardly as appears in the figures of the drawing but they are bent obliquely rearwardly as appears in Fig. 2 so that the opposed upright edges of each leg are substantially parallel and are substantially perpendicular to the meeting edge of the arcuate portion and to the axis of such arcuate portion 45 so that the load strain is borne directly along a line extending longitudinally and substantially midway the edges of the legs.

50 Each leg is bent outwardly at its lower end

forming a foot 16 which may be perforated as appears at 18 to receive suitable nails or other fastening means to secure the block to the floor of the car upon which the vehicles are being transported. Each edge of the legs 53 and the arcuate portion is shown as rolled over as at 20 and I provide a reinforcing brace member 22. This brace member has the shape generally of an inverted V and the arms 24 thereof meet at a common point along the edge of the arcuate portion 12 and extend downwardly diagonally to engage the adjacent side of the leg at a point in proximity to its foot. The above structure is that shown in the first three figures of the drawing. 59

In Fig. 4 I have shown a simple structure formed entirely of a single piece of metal and wherein the upper end of each leg portion 14 is bent underneath the adjacent side portion of the arcuate part 12 so as to form a marginal fold 26. The leg portion then is bent downwardly from a point 28 underneath and spaced from the edge of the arcuate portion flaring outwardly as shown in the figure 75 of the drawing and extending rearwardly as is shown in Fig. 2 of the drawing.

The leg portions are here provided with feet 16 as has been heretofore described. The entire structure is preferably corrugated as has been heretofore described and the load strain rests more directly upon the legs and the transverse reinforcing power may, as shown, be eliminated. An additional meritorious feature is that with my improved loading block relatively small and light nails 80 may be used to secure the blocks to the floor of the car which will not materially damage the floor. 85

What I claim is:

1. A loading block formed of relatively light sheet metal and comprising an arcuate wheel engaging portion having a pair of leg portions bent downwardly on opposite sides thereof and extending rearwardly obliquely therefrom, and an inverted generally V-shaped brace member extending from one end of the arcuate portion to each leg adjacent its foot. 95

2. A loading block formed of a strip of longitudinally corrugated light sheet metal 100

bent transversely to form an arcuate portion shaped to embrace the periphery of the wheel and having on each side a downwardly bent leg portion extending obliquely rearwardly from the arcuate portion so that the corrugations of the leg portions are substantially perpendicular to the axis of the arcuate portion, and a brace extending from each leg portion diagonally to the adjacent end of the arcuate portion.

10 In testimony whereof, I, CARL B. PARSONS, sign this specification.

CARL B. PARSONS.
